RAILWAY SAFETY AND SIGNAL DEVICE.
APPLICATION FILED DEC. 2, 1912.

Patented Oct. 27, 1914.

2 SHEETS-SHEET 2.

UNITED STATES PATENT OFFICE.

EDWARD FREED, OF SEATTLE, WASHINGTON, ASSIGNOR, BY DIRECT AND MESNE ASSIGNMENTS, TO RAILWAY SAFETY APPLIANCE COMPANY, INC., OF SEATTLE, WASHINGTON, A CORPORATION OF WASHINGTON.

RAILWAY SAFETY AND SIGNAL DEVICE.

1,114,977.

Specification of Letters Patent.

Patented Oct. 27, 1914.

Application filed December 2, 1912. Serial No. 734,489.

To all whom it may concern:

Be it known that I, EDWARD FREED, a citizen of the United States, residing at Seattle, in the county of King and State of Washington, have invented certain new and useful Improvements in Railway Safety and Signal Devices, of which the following is a specification.

This invention relates to safety appliances for railway systems; and its object is the provision of improved devices of this character whereby automatically controlled signal appliances are actuated to safeguard trains against collision.

The invention consists in the novel construction and combination of parts, as will be hereinafter described and claimed.

In the accompanying drawings, Figure 1 is a plan view of a portion of a railway track and associated parts equipped with devices embodying the present invention. Fig. 2 is a side elevation of the same together with a locomotive provided with devices to coöperate with the track equipment. Fig. 3 is an end elevation of a semaphore tower such as used at each end of a block section of track. Fig. 4 is a similar view of one of the car signal controllers. Fig. 5 is a longitudinal vertical section taken through an actuator for one of the signal controllers. Fig. 6 is a vertical transverse section through 6—6 of Fig. 5. Fig. 7 is a fragmentary horizontal section of the engineer's cab of a locomotive to illustrate the mechanism employed for operating a whistle controlling line. Fig. 8 is a diagrammatic view illustrating the preferred form of electrical connections and devices for operating a crossing signal light. Fig. 9 is a detail elevational view of the preferred form of latch-bar for securing the whistle-operating mechanism in operative condition.

In the following description I will particularly describe the mechanism upon but one side of the track and which are controlled by cars or trains traveling in but one direction. It is to be understood, however, that these devices will be duplicated upon the opposite side to accommodate cars traveling in a contrary direction, and are illustrated in Fig. 2.

The reference numeral 10 represents a railway track.

11 is a locomotive having secured thereto

a transversely arranged bar 12 which is disposed to protrude for a distance to one side of the locomotive.

Fulcrumed in suitable supports provided on the side of the locomotive cab is a bell crank lever having an arm 13 (Fig. 7) which is yieldingly held by a spring 14 in position to project laterally from the car while the other arm 15 of the lever is connected by a line 16 with a steam whistle (not shown) for causing the same to become operative when the lever arm 13 is thrust rearwardly by encountering an object in its path during the progressive travel of the car. When the lever is thus influenced it is swung into the dotted line position in Fig. 7 and a hooked finger 13¹ provided on the lever arm 13 is engaged by a spring actuated latch 17 to retain the lever in operative position with a consequent uninterrupted blowing of the whistle until the engineer releases the lever from the latch.

Provided at one side of the track and at each end of a block section of the same is a semaphore tower 18 having near the upper end of each a receptacle for a lantern 19, or its equivalent, with sight apertures at the opposite sides and which may be glazed by transparent, or "white" panes.

Pivotedly connected by a pin 20 to a tower is a pair of semaphore blades 21 provided with openings 22 in which are red glasses, as conventionally used in railway service to designate danger when brought opposite the sight apertures of the lantern receptacle.

Each pair of semaphore blades are connected to move as a single piece and, as shown in Fig. 3, are connected by a link 23 with the arm 24 of a lever which is fulcrumed at 25 to a tower and has its other arm 26 weighted so as to normally retain the arm 24 in the elevated position as indicated by full lines in the view.

27 represents a spring acting supplementary to the power of said weighted arm for rendering the upward tilting of the arm 24 more rapid. The arms 24 of both of said semaphores are connected by drag lines 28 which pass about guide pulleys, such as 29, and extend over a grooved fair leader wheel 30 which is mounted upon a rotary shaft 31 journaled in side walls of a casing 32 (Fig. 5) and is connected to the end of a plate 33. This plate is of a substantially triangular

configuration and, intermediate its length, is pivotally connected by a pin 33³ to the casing 32 and serves as a lever. The end of such lever opposite that to which drag lines 28 are connected, is attached to an extensible spring 35 which acts to swing the lever up into the position in which it is illustrated in the drawings.

The referred to casing is located at a short distance from the semaphore tower at the end of the block section from which a train enters. As the locomotive passes the casing 32 bar 12 encounters the inclined edge 33¹ of the plate and depresses the latter with the result that the aforesaid semaphore blades 21 and the lever arms 24 are respectively swung through the medium of the drag lines 28 to occupy positions indicated by broken lines in Fig. 3 to expose the red lights of the semaphore blades and also protrude the arms 24 of the respective towers within the path of the car arm 13 to render the same operative to blow the whistle should any car so equipped undertake to pass from either direction into the block section. When the plate 33 is swung down as above explained, a spring actuated lever pawl 34 engages the same within a recess 33² provided in the plate to temporarily hold it in such depressed position until the pawl is disengaged. To such an end there is provided near the exit end of a block section a tripper plate 35 (Fig. 2) pivotally supported by a pin 36 and is connected with said pawl by a line 37 passing about suitably disposed guide pulleys and a fair leader wheel 38.

Located between the semaphore towers of each block section is a post 39 having a lever 40 fulcrumed thereto by a pin 41 (Fig. 4), the lever being at such an elevation that when swung down into the dotted line position it will be in the path of the car arm 13 to cause the latter to become operative with respect to the car whistle. The function of the lever 40 is to serve as a warning to a car upon one block section of the presence of another car or train in the section next ahead.

The lever arm is normally held in its elevated position by means of a spring 42 and is drawn downwardly by means of a line 43 extending to and controlled by a lever plate 44 disposed to be engaged by the car-arm 12 just before the car leaves the block section. The lever plate 44 is secured in its lowered position by a lever pawl similar to that designated by 34. The pawl for the lever-plate 44 is, in turn, disengaged through the instrumentality of a line connected to a tripper-plate in the block section next ahead and occupying the same relative position in that block section as the plate 33 which is operatively connected to the plate corresponding to 44 in the section next behind.

Where there is a road crossing the track within any block section, gate-bars 46 are provided. These gate-bars are in the nature of levers which are fulcrumed by pins 47 to posts 48 at opposite sides of the track and are provided with counterweights 49 which serve to raise the levers clear of vehicles, etc. The gate bars are connected by lines with an operating plate 50 which is controlled by the car bar 12, as before explained, with respect to the plate utilized for controlling the semaphore arms. The plate 50 is likewise engaged by a pawl lever which is disengaged by a tripper plate 51 encountered by the car bar 12 after the same has been carried with a car or train beyond the road crossing. Upon being disengaged by its lever pawl the counterweights 49 assert their power to elevate the gate bars.

As a notice to travelers upon the cross road of the approach of a train and operative prior to the closing of the road by the gate bars, I provide a signal light, denoted by 52 in Fig. 2, which is illuminated through the agency of an electric current passing through a normally incomplete circuit which is closed by an electric switch 53 which, in turn, is operated by a lever plate 54. After the train or car has passed the crossing another electric switch 55 is actuated by a suitable device such as the tripper plate 51.

The electric light wire connections and operating devices therefor are illustrated in Fig. 8. The switches therein shown are of the three-way type having terminals *a*—*a*¹ and *b*—*b*¹ which are directly connected by wires *c* and *d*. The other terminals *e*—*e*¹ and *f*—*f*¹ of the respective switches are connected in pairs by circuit wires *g* and *h* with the generator and include the lamp 52. Switch 53 is provided with a gap closure *l* which is mounted upon an arbor *m* which also carries a ratchet wheel *o* having four teeth which are successively engaged by a pawl 56 depending from the plate 54. The other switch 55 is similarly provided with gap closure *l*¹ upon an arbor *m*¹ having mounted thereon a ratchet wheel *o*¹ which is controlled by a pawl 57 depending from the tripper plate 51.

Assuming that the gap closures *l* and *l*¹ are in the positions in which they are represented in Fig. 8, then when the plate 54 is depressed the pawl 56 will cause the closure *l* to be swung into the dotted line position indicated by *l*², whereupon the light circuit is completed and the lamp 52 is illuminated. When the car passes the tripper plate 51 the latter is depressed and the closure *l*¹ is rotated by the pawl 57 into the dotted line position *l*³ resulting in the circuit being broken and the extinguishing of the light. The next car which travels over the line will influence the switch 53 to restore the closure *l*².

7 thereof into its full line position resulting in the closing of the circuit in conformity to the then relative position of the closure of the other switch.

5 Springs are desirably applied to the various levers and blades for restoring the same more quickly to their inoperative positions although counterweights may be used instead of the springs. Also spiral springs 10 may be employed in the various fairleader wheels to coöperate with the springs provided for the respective lever plates to render the movements of the lines more rapid when the associated plates are released, an 15 example of such a spring is indicated by 58 in Fig. 5.

The invention it is believed will be understood from the foregoing description and the advantages afforded by the same are obvious.

20 What I claim is—

1. The combination with a section of railway track and a semaphore tower, a semaphore blade on the tower, and a lever on the tower operatively connected with the semaphore blade, of a plate lever disposed at a distance from said tower at one side of said track, a spring tending to yieldingly hold the plate lever in its elevated position, operative connections between the plate lever and 25 the tower lever, a means on a car for encountering said plate lever whereby the semaphore blade and its associated lever are caused to be moved into operative positions, appliances carried by the car and engageable 30 with the tower lever whereby an alarm is actuated on the car when the latter passes the tower while the lever thereof is in operative position, a spring-actuated lever pawl for retaining said plate lever in position to 35 maintain the tower lever in operative position, and a second plate lever operatively connected with said lever pawl for disengaging the latter from the aforesaid plate lever when the second named plate lever is influ- 40 45 enced by said means.

2. The combination with a section of railway track and a semaphore tower at each end thereof, a semaphore blade on each tower, and a lever on each of the towers and

operatively connected with the respective 50 semaphore blades, of a plate lever disposed at a distance from said towers and at one side of said track, a spring tending to yieldingly hold the plate lever in its elevated position, operative connections between the 55 plate lever and the tower levers, a means provided on the car for encountering said plate lever whereby the semaphore blades and the associated levers are caused to be moved into operative positions, appliances carried 60 by the car and engageable with the tower levers whereby an alarm is actuated on the car when the latter passes either of the towers while the levers thereof are in operative positions, a lever pawl for retaining the 65 plate lever in position to maintain the tower levers in operative positions, and a second plate lever operatively connected with said pawl for disengaging the latter from the aforesaid plate lever when the second named 70 plate lever is influenced by said means.

3. The combination with a railway track divided into block sections, locomotives, whistle actuating devices connected to the locomotive cabs, and a bar carried by each 75 locomotive and protruding from the sides thereof, of a semaphore tower at each end of a section, a lever pivotally connected to each of said towers, a spring-actuated plate lever having an inclined upper edge provided at 80 the side of the track and engageable by the bar of a locomotive whereby the respective levers of a track section are moved into position to be engaged by the whistle actuating means of the other locomotive to render such 85 means operative should the last named locomotive enter a section previously occupied by another locomotive, and devices engageable by said whistle actuating means for rendering the latter operative where a locomotive is in the adjacent section. 90

Signed at Seattle, Wash., this 19th day of November, 1912.

EDWARD FREED.
